UNITED STATES PATENT OFFICE.

JACOB GOLDHABER, OF JOHNSTOWN, PENNSYLVANIA.

DESIGN FOR A BOTTLE OR SIMILAR ARTICLE OF MANUFACTURE.

Application filed October 8, 1928. Serial No. 28,412. Term of patent 14 years.

To all whom it may concern:

Be it known that I, JACOB GOLDHABER, a citizen of the United States, residing at Johnstown, in the county of Cambria and State of Pennsylvania, have invented a new, original, and ornamental Design for Bottle or Similar Article of Manufacture.

The figure is a face view showing my new bottle design. The opposite side of the bottle is substantially a duplicate of the portion appearing in the figure.

I claim:

The ornamental design for a bottle or similar article of manufacture as shown and described.

September 1st, 1928.

JACOB GOLDHABER.
